FIG. 1

Patented Sept. 19, 1922.

1,429,833

UNITED STATES PATENT OFFICE.

WARREN H. BEALL, OF WASHINGTON, DISTRICT OF COLUMBIA.

BUILDING DOOR.

Application filed October 5, 1921. Serial No. 505,596.

To all whom it may concern:

Be it known that I, WARREN H. BEALL, a citizen of the United States of America, residing at Washington, in the District of Columbia, have invented certain new and useful Improvements in Building Doors, of which the following is a specification.

This invention relates to certain new and useful improvements in garage and other building doors and has particular reference to the idea of a sliding door arrangement where one of the doors in its sliding movement is moved to an overlapping position with relation to the other door.

The primary object of the invention resides in the provision of a door for a garage or other buildings wherein a pair of sliding doors is mounted for movements to overlie each other with the doors constructed in a manner to present substantially more than one-half of the door opening as an entrance for an automobile or other vehicle.

A further object of the invention embodies in a garage door construction, a sliding arrangement of the doors with a hinged door carried by the inner edge of one of the doors for overlapping the sliding door carrying the same to present an entrance opening at either side of the garage considerably greater than one-half the distance across the garage door opening.

A still further object of the invention has particular reference to the mounting of a hinged jamb strip carried by the inner end of one of the sliding doors that constitutes an abutment or stop for the swinging end of a hinged door carried by the inner end of the other sliding door.

Another object of the invention has reference to a garage door of the type above set forth wherein cooperating lock devices are carried by the inner edge of the hinged jamb strip and the swinging edge of the hinged door.

The invention further embodies the idea of forming the jamb strip in the manner of an angle extension carried by the free edge of the hinged door, this arrangement permitting the application of a padlock and hasp upon the outer side of the garage door.

With the above general objects in view and others that will appear as the nature of the invention is better understood, the

same consists of the novel form, combination and arrangement of parts hereinafter more fully described, shown in the accompanying drawing and claimed.

In the drawing, wherein like reference characters designate corresponding parts throughout the several views,

Figure 1 is a horizontal sectional view of the garage doors in closed position, a portion of the garage being shown in section,

Figure 2 is a horizontal sectional view similar to Fig. 1 showing the garage doors moved to an open position at one side of the garage presenting substantially more than one-half of the garage door opening at one side thereof,

Figure 3 is a horizontal sectional view similar to Fig. 1 showing the garage doors slid to the opposite side of the garage and with the jamb strip moved outwardly of the sliding door carrying the same to permit the sliding overlapping arrangement of the opposite garage door and presenting at the opposite side of the garage substantially more than one-half of the door opening space,

Figure 4 is a horizontal sectional view of a modified form of garage door wherein the jamb strip is carried by the hinged door, and

Figure 5 is a perspective view of the front end of a garage showing the hinged jamb strip carried by one of the sliding doors and with the hinged door partially opened.

In the building of garages and similar structures for housing automobiles and other vehicles, wherein at least two vehicles are housed within the structure, various types of door constructions have been devised for increasing the door entrance opening for the automobile. One type of garage door now in use for increasing the door opening of the garage disposes the door, when in an open position, within the garage adjacent the side wall thereof, the door when in open position occupying a space within the garage and also, when being moved to the open position traversing the interior of the garage at a point materially spaced from the side walls, necessitating the positioning of the car considerable distance from the side wall to accommodate the opening movement of the door. In other doors of the folding type the same are also moved within the garage and

occupy space within the garage that is well adapted for shelves, work benches or the like.

The construction and arrangement of garage doors disclosed in this application when moved to an open position present substantially more than one half of the garage door opening for the entrance of one car at each side of the garage permitting an automobile to enter the garage from a comparatively narrow driveway extending at right angles to the garage door opening without necessitating rearward movement of the automobile to aline the same with the housing space in the garage.

Briefly described, the garage door construction embodies a pair of sliding doors overlapping each other when one of the doors is in an open position while a hinged door extending the entire height of the sliding doors is carried by the inner end of one of the sliding doors. A hinged jamb strip is carried by the inner end of the other sliding door and has the free swinging edge thereof projecting inwardly of the sliding door carrying the same and in line with the opposite sliding door, the inner edge of the hinged jamb strip being positioned for abutting engagement with the free swinging edge of the hinged door. Stop bars are carried by the opposite faces of the jamb strip, one of the bars being engaged by the free edge of the hinged door while the other bar engages the inner face of the sliding door carrying the jamb strip to form a snug engagement between the jamb strip and sliding door when the jamb strip is in operative position. To hold the jamb strip in closed operative position a hook and eye connection is established between the jamb strip and sliding door carrying the same. A suitable slide bolt lock is cooperatively carried by the hinged jamb strip and the hinged door, being manually operable from within, and key operated from the outer side of the door. In another form of the invention the jamb strip forms an integral part of the hinged door projecting outwardly thereof at right angles for abutting engagement with the cooperating sliding door and permitting of the employment of a hasp and padlock upon the outer side of the garage door.

Referring more in detail to the accompanying drawing and particularly to Figs. 1 to 3 and 5 there is illustrated a garage 1 having a floor space 2 and an entrance opening 3 extending completely across the garage.

60 The closure doors associated with the opening 2 embody transversely sliding doors 4 and 5 offset as illustrated to be moved to overlapping position when either of the doors is open, floor guides 6 and 7 being provided for the doors 4 and 5 respectively.

The width of each door is substantially less than one-half the width of the garage door opening, leaving a central space between the inner ends of the sliding doors to accommodate a middle door 8 hinged as at 9 to the inner end of the sliding door 5, the hinged door 8 moving inwardly when in an open position as illustrated in Fig. 2.

An abutment stop for the hinged door 8 in the form of a jamb strip 10 is hinged as at 11 to the outer corner edge of the inner end of the sliding door 4, the jamb strip 10 when in the closed position shown in Fig. 1 extending inwardly of the sliding door 4 and across the sliding space for the sliding door 5. To provide for a close fitting engagement between the jamb structure and sliding door when the same is in closed position a bar 12 carried by one side face of the jamb strip 10 is moved to engagement with the inner face of the sliding door 4 as clearly shown in Fig. 1, and to lock the jamb strip in closed position a hook 13 carried by the jamb strip 10 engages a keeper or eye 14 countersunk within the inner face of the door 4 so that no obstructions will project from the door 4 for engagement by the sliding door 5.

The hinged door 8 is locked in a closed position by a sliding bolt lock 15 cooperatively carried by the inner face of the hinged door 8 and the inner edge of the jamb strip 10, the bolt lock 15 being manually operable from within the garage while the lock 15 is releasable at the outer side of the door by inserting a key in the key opening 16 as clearly shown in Fig. 5. The door 8 is limited in its closing movement by engaging the bar 10^a carried by the outer face of the jamb strip 10, and when so engaged the cooperating members of the sliding bolt lock 15 are properly positioned.

In the operation of the doors, assuming that an automobile is to be placed within the space indicated by the reference character A in Fig. 2 the lock 15 is released permitting the hinged door 8 to be swung to open position shown in Fig. 2. The jamb strip 10 is then moved to a position outwardly of the sliding door 4 carrying the same by releasing the hook 13 and permitting the sliding door to be moved to a position overlying the sliding door 5 as illustrated, thus presenting substantially more than one-half of the garage door opening for the entrance of a single automobile at the point A. By moving the jamb strip 10 outwardly as shown in Fig. 2 the inner end thereof is displaced from the sliding path of movement of the door 4 and further spaced outwardly of the sliding door 5. In placing an automobile in the space indicated by the reference character B in Fig. 3 the doors are opened in a similar manner, the hinged door 8 being moved to the position shown in

Fig. 2 and the hinged jamb strip 10 swung outwardly as indicated at Fig. 3 to displace the same from the path of movement of the sliding door 5, thereby permitting the sliding door 5 to move inwardly and into overlapping relation with the door 4, the guide blocks 6 and 7 directing the movements of the respective doors as will at once be understood, it being noted that when the hinged door 8 is opened, as shown in Fig. 2, and the jamb strip 10 swung outwardly to the position shown in Figs. 2 and 3, the hinged elements 9 and 11 provide sufficient space between the sliding doors and the hinged members to permit sliding movement of the doors 4 and 5 with the guides 6 and 7 clearing the space between the doors and the hinged elements.

A modified form of the invention is shown in Fig. 4 wherein the jamb strip forms an integral part of the hinged door 8, the jamb strip 16 being in the form of an angle projection extending outwardly of the hinged door while the outer face of the jamb strip 16 carries a bar 17 for engaging the inner face of the sliding door 4 to limit the closing movement of the hinged door and permitting the employment of a hasp 18 and a padlock 19 for securing the doors in locked position at the outer side of the garage. It will, therefore be seen that the opening movement of the hinged door 8 as shown in Fig. 4 will permit the sliding movement of either of the sliding doors 4 or 5, movement of the door displacing the movement of jamb 16 from the path of movement of the sliding door 4, permitting the sliding doors 4 and 5 of this form of the invention to assume either of the positions as shown in Figs. 2 and 3.

With a door structure as above set forth it is unnecessary to provide a locking connection between the doors and the floor 2 of the garage, the locking connection between the sliding doors 4 and 5 being at the jamb section 10 and the swinging door 8.

While there are herein shown and described the preferred embodiments of the present invention, it is nevertheless to be understood that minor changes may be made therein without departing from the spirit and scope of the invention.

What is claimed as new is:—

1. A door construction for garages and the like comprising sliding doors so mounted as to overlie each other when either door is opened and spaced at their adjacent ends when the doors are closed, a hinged door carried by the inner end of one sliding door and adapted to be locked to the inner end of the other sliding door.

2. A door construction for garages and the like comprising sliding doors so mounted as to overlie each other when either door is opened and spaced at their adjacent ends

when the doors are closed, a hinged door carried by the inner end of one sliding door, and a jamb strip carried by the inner end of the other sliding door to be engaged by the free edge of the hinged door. 70

3. A door construction for garages and the like comprising sliding doors so mounted as to overlie each other when either door is opened and spaced at their adjacent ends when the doors are closed, a hinged door carried by the inner end of one sliding door, a jamb strip carried by the inner end of the other sliding door to be engaged by the free edge of the hinged door, and a lock connection between the hinged door and 80 jamb strip.

4. A door construction for garages and the like comprising sliding doors so mounted as to overlie each other when either door is opened and spaced at their adjacent ends 85 when the doors are closed, a hinged door carried by the inner end of one sliding door and a jamb hingedly carried by the inner end of the other sliding door and traversing the sliding space of the first named door, 90 and a lock connection between the hinged door and the jamb strip.

5. A door construction for garages and the like comprising sliding doors so mounted as to overlie each other when either door 95 is opened and spaced at their adjacent ends when the doors are closed, a hinged door carried by the inner end of one sliding door and a jamb hingedly carried by the inner end of the other sliding door and traversing 100 the sliding space of the first named door, a lock connected between the hinged door and the jamb strip, and stop bars carried by the opposite faces of the jamb strip for limiting the closing movement of the hinged door 105 and engaging the face of the sliding door carrying the jamb strip respectively.

6. A door construction for garages and the like comprising sliding doors so mounted as to overlie each other when either door 110 is opened and spaced at their adjacent ends when the doors are closed, a hinged door carried by the inner end of one sliding door and a jamb hingedly carried by the inner end of the other sliding door and traversing 115 the sliding space of the first named door, a lock connection between the hinged door and the jamb strip, and means for holding the jamb strip in closed position.

7. A door construction for garages and the like comprising sliding doors so mounted as to overlie each other when either door is opened and spaced at their adjacent ends when the doors are closed, a hinged door carried by the inner end of one sliding door 120 and a jamb hingedly carried by the inner end of the other sliding door and traversing the sliding space of the first named door, a lock connection between the hinged door and the jamb strip, stop bars carried by the 125

130

- opposite faces of the jamb strip for limiting the closing movement of the hinged door and engaging the face of the sliding door carrying the jamb strip respectively, and means 5 for holding the jamb strip in closed position.
8. A door construction for garages and the like comprising doors mounted for sliding overlapping relation, and a perpendicular jamb strip carried by one of the doors 10 adapted to be moved into and out of the path of sliding movement of the doors.
9. A door construction for garages and the like comprising doors mounted for movement in overlapping relation, and a hinged 15 jamb strip carried by one of the doors adapted to be removed into and out of the path of movement of the doors.
10. A door construction for garages and the like comprising doors mounted for sliding overlapping relations, a hinged door carried by the inner end of one of the sliding doors, and means associated with the free end of the hinged door and the adjacent 20 end of the opposite sliding door to form an abutment for the hinged door and to control the movement of the sliding doors.
11. A door construction for garages and the like comprising doors mounted for sliding overlapping relations, a hinged door carried 25 by the inner end of one of the sliding doors,
- and movable means associated with the free end of the hinged door and the adjacent end of the opposite sliding door to form an abutment for the hinged door and to control the movement of the sliding doors. 35
12. In a door construction, a pair of doors, and a jamb strip carried by one of the doors and normally lying in the path of movement of the other door and adapted to be shifted to permit free movement of both doors. 40
13. In a door construction, a pair of doors, and a jamb strip hingedly connected to the edge of one of the doors and normally lying in the path of movement of the other door and adapted to be shifted to permit 45 free movement of both doors.
14. In a door construction, sliding doors, and a jamb strip hingedly connected to the edge of one of the doors and normally lying in the path of sliding movement of the doors 50 and adapted to be swung to a position to permit free sliding movements of the doors.
15. In a door construction, sliding doors, and a jamb strip associated with the doors and normally lying in the path of sliding 55 movements of the doors and adapted to be moved to a position laterally of the path of sliding movement of the doors.

In testimony whereof I affix my signature.
WARREN H. BEALL.
